LIGHTING FIXTURE

Filed Aug. 19, 1930

UNITED STATES PATENT OFFICE

GEORGE L. BARNES, OF LOS ANGELES, CALIFORNIA

LIGHTING FIXTURE

Application filed August 19, 1930. Serial No. 476,383.

My invention relates to and has for a purpose the provision of a lighting fixture particularly adapted although not necessarily, for outdoor lighting systems and embodying the desirable qualities of simplicity, durability, weather-proofness, and inexpensiveness of construction as well as its capability of being installed with the utmost ease and dispatch.

It is another purpose of my invention to provide a lighting fixture of the above described character capable of being suspended from a supporting wire or pipe in outdoor systems or from chain and loop in indoor systems, and of being associated with feed wires in a manner to maintain them definitely spaced apart and/or readily connected to a socket in the fixture.

It is a further purpose of my invention to provide a lighting fixture embodying a reflector composed of an outer section and an inner socket supporting section detachably associated with the outer section and co-acting therewith to form a compartment into which feed wires are readily introduced and connected to the socket with the utmost ease when the sections are disassembled, all while permitting the sections to be readily assembled when the necessary wire connections have been made so that the installation of the fixture is greatly facilitated.

I will describe only three forms of lighting fixture embodying my invention, and will then point out the novel features thereof in claims.

In the accompanying drawing:

Figure 1 is a view showing in plan, one form of lighting fixture embodying my invention.

Figure 2 is a vertical sectional view taken on the line 2—2 of Figure 1.

Figure 3 is a fragmentary vertical sectional view of another form of lighting fixture embodying my invention, and

Figure 4 is a fragmentary vertical sectional view of a third form of lighting fixture embodying my invention.

Referring specifically to the drawing and more particularly to Figures 1 and 2, my invention in its present embodiment comprises

a reflector designated generally at R and composed of an outer section 10 and an inner section 11 preferably constructed of sheet metal of suitable gage. The section 10 is formed to provide an inverted cup or dome-shaped portion 12 from which depends and flares outwardly an annular portion or flange 13 of concavo-convex cross-section, having its underside suitably treated to provide a reflecting surface 14. The section 11 is in the form of a disk of concavo-convex cross-section, the peripheral edge of which seats in an annular groove 15 formed in the section 10 at the juncture between its portions 12 and 13.

The under side of the section 11 is suitably treated to provide a reflecting surface 16 forming a continuation of the reflecting surface 14 of the section 10, and the two sections are secured together by two bolts 17 extending through diametrically opposed openings in the dome shaped portion 12 and through slots 18 in the section 11, the bolts being provided with nuts 19 for clamping the two sections together.

In the form shown in Figures 1 and 2, the bolts 17 are of sufficient length to receive exteriorly of the section 10, conventional two part insulators 20 which co-act to clamp thereto by means of other nuts 21 on the bolts, feed wires 22 and 23 from which are tapped branch wires 24 and 25 insertable through diametrically opposed slots 26 in the dome shaped portion 10, into a compartment 27 which the two reflector sections 11 co-act to form when they are assembled as shown in the drawing.

The slots 26 are formed by extruding the metal of the section 10 so as to provide hoods 28 which function to prevent the ingress of water through the slots into the compartment 27. The section 11 is provided with a central opening in which is received and secured, a conventional two part lamp socket 29 providing a socket section 29^a into which a lamp L is screwed, as well as providing terminals 29^b and 29^c in the compartment 27 for the connection of the branch wires 24 and 25 thereto to supply current to the lamp.

The dome shaped portion 12 of the sec-

tion 10 is provided centrally thereof with an opening through which extends the threaded shank 30 of an eye bolt E secured to the section 10 by a nut 31 and washer 32 on the shank. Through the eye 33 of the bolt E is adapted to be freely extended, a supporting wire or cable 34 adapted to be strung between posts (not shown) so that the wire co-acts with the eye in suspending the fixture at a desired elevation and location along the length of the wire.

In installing the form of fixture above described, the supporting wire 34 is passed through the eye 33 of the bolt E, after which the previously strung feed wires 22 and 23 are clamped to the insulators 20 by the bolts 17 and the nuts 21 so that the feed wires will be supported from the fixture and be maintained in definite spaced relation.

The branch wires 24 and 25 are now connected to the feed wires and can be clamped with the latter by the insulators as shown. The free ends of the branch wires are then passed through the slots 26 in the section 10, and it will be understood that the branch wires are of sufficient length to permit their easy connection to the terminals of the lamp socket 29 when applied to the section 11, and with the latter disassembled from the section 10 by removing the nuts 19. When the connection of the branch wires to the terminals of the sign receptacle has been made, the section 11 is applied to the section 10 so that the free ends of the bolts 17 extend through the slots 18 in the section 11, after which the nuts 19 are applied to the bolts, to thus secure the two reflector sections together, with the terminals of the sign receptacle and any excess length of the branch wires enclosed in the weatherproof compartment 27. The lamp L can now be screwed into the socket of the receptacle 29 so that with the feed wires included in circuit with a source of current supply, the fixture will be ready for use.

It will be manifest from the foregoing description that the fixture will be suspended solely by the supporting wire 34, and that the feed wires 22 and 23 will in turn be supported and maintained in spaced relation by the fixture, all in such manner as to permit the necessary connections of the feed wires to supply current to a lamp in the fixture, with the utmost ease and dispatch.

Referring now to Figure 3 I have herein shown another form of lighting fixture embodying my invention and particularly adapted for outdoor use with a supporting pipe 35 carrying the feed wires 36 and 37. This form of fixture is identical in construction to the first form with the exception that the insulators 20 as well as the slots 26 in the reflector section 10 are dispensed with; the free end of the pipe 35 being extended

65 through a central opening in the portion 12

of the section 10, and being threaded externally to receive nuts 39 for securing the section 10 to the pipe. The feed wires 36 and 37 are of sufficient length to permit of their connection to the receptacle 29 in the same manner as the feed wires 22 and 23 described in conjunction with the first form of my invention.

Referring now to Figure 4, I have herein shown a third form of my invention particularly adapted for indoor use with a chain 40 for suspending the fixture, which is identical in construction to the first form described with the exception that the insulators 20 and slots 26 are also dispensed with. In this instance the lower end of the chain 40 is connected to the eye 41 of an eye bolt E having a tubular externally threaded shank 42 extending through a central opening in the portion 12 of the reflector section 10 and secured to the latter by a nut 43. The feed wires 44 and 45 are passed through the links of the chain 40 and then through the tubular shank 42 for connection to the receptacle 29 in the same manner as the feed wires 22 and 23 described in the first form of my invention.

It will be understood that as the insulators 20 are dispensed with in the forms of my invention shown in Figure 3 and 4, that the bolts 17 need only be of sufficient length to pass through the sections 10 and 11 and receive the nuts 19 for securing the two sections together, and it will be manifest that in all forms of my invention, the section 10 and the section 11 having the socket 29 are secured together in the same manner to form the compartment 27, and thus permit the connection of feed wires to the receptacle with the utmost ease and dispatch, all while enclosing the terminals of the receptacle and any excess length of the wires in the compartment when the sections are assembled.

Although I have herein shown and described only three forms of lighting fixture embodying my invention, it is to be understood that various changes and modifications may be made therein without departing from the spirit of the invention and the spirit and scope of the appended claims.

I claim:

1. A lighting fixture comprising two reflector sections coacting to provide a compartment having an opening through which feed wires are adapted to be extended into the compartment, one of the reflector sections having a lamp socket provided with terminals disposed in said compartment and to which the feed wires are adapted to be connected, bolts having nuts thereon for securing the sections together, and insulators on the bolts to which the feed wires are adapted to be connected to support the feed wires from the fixture.
2. A lighting fixture comprising an outer

reflector section and an inner reflector section coating to provide a compartment, fastening members at spaced locations for securing the sections together, insulators supported on the outer section by the fastening members and to which feed wires are adapted to be connected and be thereby supported from the fixture in spaced relation, the outer section having openings through which branch wires from the feed wires are adapted to be extended into the compartment, and a lamp socket supported by the inner section and having terminals disposed in the compartment and to which the branch wires are adapted to be connected.

3. A lighting fixture comprising a reflector section, bolts extending through the section, insulators on the bolts, nuts on the bolts co-acting therewith to secure the insulators to the section, a second reflector section coacting with the first reflector section to provide a compartment, and having openings through which the bolts extend, other nuts on the bolts coacting therewith to secure the reflector sections together, one of the reflector sections having openings through which feed wires are adapted to be extended into the compartment, and a lamp socket supported by one of the reflector sections and having terminals disposed in said compartment, to which the feed wires are adapted to be connected.

4. A lighting fixture comprising an outer reflector section having an inverted cup shaped portion and an annular portion depending from the first portion, an inner reflector section coacting with the first said portion to provide a compartment having an opening through which feed wires are adapted to be extended into the compartment, a lamp socket supported by the inner reflector section and having terminals disposed in said compartment, to which the feed wires are adapted to be connected, bolts having nuts co-acting therewith to secure the sections together, and insulators on the bolts, to which the feed wires are adapted to be secured and be thereby supported from the fixture.

5. A lighting fixture having two reflector sections co-acting to form a compartment provided with an opening for conductors; fastening members for securing the reflector sections together; and insulators to which conductors are adapted to be secured for connection to terminals in the compartment, supported by the fastening members on one of the reflector sections.

6. A lighting fixture having two reflector sections co-acting to form a compartment provided with an opening for conductors; fastening members for securing the reflector sections together; and insulators to which conductors are adapted to be secured for connection to terminals in the compartment, supported by the fastening members on one of the reflector sections; the fastening members

each including a part separable therefrom to enable one reflector section to be detached from the other while the insulators remain supported on said reflector section.

7. A lighting fixture having two reflector sections co-acting to form a compartment provided with an opening for a conductor; an insulator to which a conductor is adapted to be secured for connection to a terminal in the compartment; and means co-acting with the insulator and reflector sections, to support the insulator on the reflector and secure the reflector sections together.

8. A lighting fixture having two reflector sections co-acting to form a compartment provided with an opening for a conductor; an insulator to which a conductor is adapted to be secured for connection to a terminal in the compartment; and means co-acting with the insulator and reflector sections, to support the insulator on the reflector and secure the reflector sections together, said means including a separable part enabling one reflector section to be detached from the other while the insulator remains supported on said reflector section.

GEORGE L. BARNES.
